UNITED STATES PATENT OFFICE

147,033

DESIGN FOR A TAP KNOB OR SIMILAR ARTICLE

Harold J. Austin, Scarsdale, N. Y., assignor to Liebmann Breweries, Inc., Brooklyn, N. Y., a corporation of New York

Application April 19, 1946, Serial No. 128,785

Term of patent 14 years

(Cl. D2—3)

To all whom it may concern:

Be it known that I, Harold J. Austin, a citizen of the United States, residing at 41 Hampton Road, Scarsdale, county of Westchester, and State of New York, have invented a new, original, and ornamental Design for a Tap Knob or Similar Article, of which the following is a specification, reference being had to the accompanying drawing, forming part thereof, in which

Fig. 1 is a front view of a tap knob or similar article, showing my new design;

Fig. 2 is a side view;

Fig. 3 is a top plan view; and

Fig. 4 is a rear view thereof.

I claim:

The ornamental design for a tap knob or similar article, substantially as shown.

HAROLD J. AUSTIN.
